W. OCHSE

TOOTHBRUSH

Filed May 14, 1923

FIG. 1

FIG. 2

INVENTOR

FIG. 3

WILLIAM OCHSE,

By Ralph Kaush ATTORNEY.

UNITED STATES PATENT OFFICE.

WILLIAM OCHSE, OF SAN ANTONIO, TEXAS.

TOOTHBRUSH.

Application filed May 14, 1923. Serial No. 638,805.

To all whom it may concern:

Be it known that I, WILLIAM OCHSE, a citizen of the United States, residing at the city of San Antonio, county of Bexar, and

5 State of Texas, have invented a certain new and useful Improvement in Toothbrushes, of which the following is a specification, reference being had to the accompanying drawing, forming a part thereof.

10 This invention relates to a certain new and useful improvement in tooth-brushes and has for its chief object the provision of a brush, whose functional surface comprises both an area especially designed for the 15 cleansing of the relatively broad and flat anterior and posterior faces of the crown portions of the teeth, and also an area of relatively thin or tapering section for extension interstitially of the teeth for cleansing 20 the opposed faces of the teeth.

With the above and other objects in view, my present invention resides in the novel features of form, construction, arrangement, and combination of parts hereinafter 25 described and afterwards pointed out in the claims.

In the accompanying drawing,

Figure 1 shows in side elevation a tooth-brush constructed in accordance with my invention;

Figure 2 is a transverse sectional elevation of the brush taken approximately on the line 2—2, Figure 1; and

Figure 3 is an elevation similar to Figure 35 2 of a modified or alternate form of brush embodying my invention.

Referring now by numerals to the said drawing, 1 designates the brush back or handle, supported by which is a relatively 40 plane tooth-engaging area 2 and a tooth-engaging area comprising an element 3 of a relatively small section for extension between the teeth.

By preference, and as shown, the surface 45 or area 2 is composed of the ends of bristles, or their equivalent, arranged in tufts, such as 4, secured in the brush handle, and by further preference the area or element 3 is composed of bristles, arranged in tufts 5,

whose ends are "trimmed" to produce at- 50 tenuated or tapering bristle tufts project- ing upwardly beyond the plane of the flat ends of the tufts 4.

I prefer to construct the brush, as shown, with a row of the tufts 5, having the at- 55 tenuated or tapering bristles 3, lengthwise of the brush and relatively spaced along the longitudinal medial line of the handle, and to dispose the tufts 4 in parallel rows on op- 60 posite sides of the row of tufts 5, so that the relatively normally plane surfaces 2 formed by the flat ends of the tufts 4 contiguously parallel the attenuated or tapering bristles 3 of the tufts 5, the brush as a whole thereby 65 presenting a substantially continuous sur- face composed of bristle ends which in the same operation, or synchronously, cleanse both the anterior and posterior faces of the crowns of the teeth and the opposed or in- 70 terstitial faces of the teeth.

The modified form of brush illustrated in Figure 3 is substantially the same as the form of brush illustrated in Figures 1 and 2, except that the attenuated or tapering ele- 75 ment 3 of the brush is composed of two paral- lel rows of the tufts 5, as shown.

My new brush may be readily and inex- 80 pensively manufactured and has been found exceedingly efficient in the preservation of the teeth and useful in the remedial treat- 85 ment of pyorrhea. I am aware that minor changes in the form, construction, arrange- ment, and combination of the several parts of my new brush may be made and substi- 90 tuted for those herein shown and described without departing from the nature and prin- ciple of my invention.

Having thus described my invention, what I claim and desire to secure by Letters Patent is:

1. A tooth-brush including a back pro- 95 vided upon one face with outer rows and an intermediate row of bristle tufts, said rows of tufts extending in contiguous approxi- mately parallel relation longitudinally of the back, the free ends of the bristle tufts of the outer rows being trimmed flat to nor- 95 mally reside on the same plane and the tufts

of the intermediate row being trimmed to taper outwardly of the back beyond the flat face of the outer rows.

2. A tooth-brush including a back provided upon one face with outer and inner rows of bristle tufts, said rows of bristle tufts extending in contiguous approximately parallel relation longitudinally of the back, the

free ends of the bristle tufts of the outer rows being trimmed flat to normally reside on the same plane and the tufts of the inner rows being trimmed to taper outwardly of the back beyond the flat face of the outer rows.

In testimony whereof, I have signed my name to this specification.

WILLIAM OCHSE.
